leg 30 to shift it toward leg 31. The slope of the cam surfaces 63 and 64 is such that movement of the handle 62 through an angle of approximately 180 degrees will effect movement of the frame legs between their limit positions. The slope of the surfaces 63 and 64 is also such that the frictional resistance therebetween will prevent automatic separation of the legs 30 and 31 and when once a sheet metal piece such as 53 is clamped between the feeding rolls 40 and 41.

The tool means provided for effecting the opening of the seam lock according to the first modification of the invention comprises a pair of similar relatively thin discs 70 and 71 mounted for free rotation upon an offset end portion 72 of a shaft 73. The discs 70 and 71 are preferably provided with oppositely extending hub portions 74 and 75, providing enlarged bearing surfaces therefor with respect to the shaft portion 72. The discs 70 and 71 are preferably of hardened steel, relatively thin at their edges, and beveled outwardly toward their centers to a thickness somewhat greater than at their edges. Preferably, the angle of bevel is somewhat greater on the hub sides of the discs than on the face sides substantially as illustrated in the fragmentary enlarged view of Fig. 3. The discs 70 and 71 may be biased towards each other by means of a compression spring 76 arranged about the outer end of the shaft portion 72 between the stop washer 77 and nut 78. The outer end of the shaft portion 72 is provided with a flattened side and washer 77 with a cooperatively shaped opening so as to prevent rotation of the disc hub 74 from automatically unscrewing the nut 78. By adjusting the nut 78, the degree of separation between discs 70 and 71 can be controlled for different weights of metal.

The shaft portion 72 supporting the discs 70 and 71 is secured eccentrically onto the end of the shaft portion 73 which is journaled within a cooperating bore provided through the frame leg 31. Mounted on the outer end of the shaft 73 is a manual adjusting handle 81 by means of which the shaft 73 may be rotated for raising or lowering discs 70 and 71 with relation to the edge of the sheet metal piece clamped between the feed rolls 40 and 41. The shaft 73, in addition to being freely rotatable within the frame leg 31, is also longitudinally slidable therethrough in order to facilitate the adjustment of the disc tools into the operative position with respect to the standing edge of the sheet metal seam lock. The shaft 73 includes an enlarged portion 82 between the shaft portions 72 and 73 providing shoulders 83 and 84 on the opposite ends thereof. The shoulder 83 provides a thrust bearing surface for the hub 75 of the disc tool 71, while shoulder 84 provides a stop for limiting axial movement of the shaft 73 through the frame leg 31 to the right, as viewed in Fig. 1.

In Fig. 3 the disc tools 70 and 71 are shown in the elevated position, in which position they are placed during the clamping of the sheet metal member 53 between the feed rolls 40 and 41. To lower the disc tools 70 and 71 to the operative position, the handle 81 is rotated in the proper direction, counterclockwise as viewed in the end view of Fig. 2. Because of the bevel of the facing surfaces of the disc tools, the peripheral edges thereof are spaced apart a distance somewhat greater than the thickness of the metal of the piece 53, so that upon lowering of the discs 70

and 71 the upper extremity of the standing edge will be guided therebetween. Because of the fact that the standing edge will be variously deformed as regards its alignment with the main body of the piece 53, the supporting shaft 73 for the disc tools may be longitudinally adjusted through the frame leg 31 as necessary as the discs 70 and 71 are lowered. Following initial entry of the upper edge of the sheet metal piece between the discs 70 and 71, a continued force applied to the handle 81 will force the discs 70 and 71 downwardly until one of the discs reaches the bottom of the pocket, also forcing the standing edge portion of the lock into a parallel alignment with the body 53 and simultaneously wedging the folded wall portion of the lock outwardly into the proper spaced relation with respect to the standing edge portion. Preferably, the angle of bevel on the outer side of the discs is such that when one of the discs, as 70, is forced downwardly to the bottom of the pocket, the folded wall portion of the lock will be forced outwardly away from the standing edge portion into substantial parallel spaced relation therewith. With the disc tools 70 and 71 lowered to the operative position as illustrated in Fig. 1, the sheet metal piece 53 may be fed through the machine by rotation of the hand crank 51. The disc tools 70 and 71 will be retained in their lowered position as the sheet metal member is fed through the machine by virtue of the fact that the force applied thereagainst is in the reverse direction of rotation with respect to the supporting shaft 73 to that required for effecting upward movement of these discs. In order to limit downward movement of the disc tools 70 and 71 to the depth of the pocket in the sheet metal member 53, a screw 85 is provided in the handle 81, the lower end of which is adapted to butt against a stop 86 provided on the outer side wall of the frame leg 31 as shown more clearly in the end view of Fig. 2.

For guiding the movement of the upper edge of the sheet metal piece 53 through the machine in a predetermined straight line, a pair of guides, or gauges, 87 and 88 mounted in bosses 89 and 90 on the opposite sides of the frame leg 31 extend across the front and rear sides of the machine in parallel horizontal alignment with the upper edge of the sheet metal piece 53. These gauges may be adjusted by means of suitable set screws provided in the bosses 89 and 90, respectively.

The disc tools 70 and 71 are readily removable from the end of the shaft portion 72 by simply removing the nut 78, spring 76, and washer 77 for replacement with other tools of different sizes as may be required, depending upon the particular weight of metal being worked upon or curvature of the sheet. A second style of tools will presently be described.

Once the discs 70 and 71 are shifted to the operative position as shown in Fig. 1, the sheet metal piece 53 may be fed through the machine at a relatively high rate of speed, whereupon the seam lock is made in readiness for assembling into the final structure. The standing edge portion is straightened out smoothly and in parallel alignment with the main body of the sheet metal piece, and the folded wall portion is wedged out into a substantially parallel spaced relation with respect to the standing edge. It will be noted that while the disc 70 acts as a wedge for opening the lock pocket, it also acts as an ironer to smoothen the standing edge against the cooperating back-up disc 71. While it is not essential, it is preferred that the discs 70 and 71 be of substantially

BOTTLE CARRIER

Bertis F. Hamilton, Columbus, Ind., assignor to
Noblitt-Sparks Industries, Inc., Columbus,
Ind., a corporation of Indiana

Application August 5, 1939, Serial No. 288,491

4 Claims. (Cl. 224—48)

The present invention relates to improvements in the bottle carrier illustrated and described in the co-pending application of Nell Hamilton, Serial No. 224,175, filed August 10, 1938, issued Sept. 16, 1941, as Patent No. 2,256,451. That bottle carrier comprises a rigid bottom, sides hingedly connected thereto, and yokes which are mounted on the sides and which, when the carrier is erected, co-operate to form a handle by which the carrier and its contents may be carried.

It is the primary object of the present invention to produce a bottle carrier of this type in which accidental removal of the bottles from the carrier is positively prevented. A further object of the invention is to improve and simplify the construction of the carrier.

The accompanying drawing illustrates my invention: Fig. 1 is an end elevation of the improved carrier; Fig. 2 is a horizontal section on the line 2—2 of Fig. 1; and Fig. 3 is a fragmental view similar to Fig. 2 but on an enlarged scale and with portions of the device broken away.

The carrier illustrated comprises a rigid bottom comprising two spaced side members 15 interconnected by a series of transversely extending members 16. The ends of the cross members 16 are offset upwardly and secured, as by welding, to the side members 15. The sides of the carrier are formed of pieces of sheet metal 17 hingedly connected respectively to the two side members 15 of the bottom, such hinged connection desirably being effected by providing each side 17 along its lower edge with a series of ears 18 which are bent to embrace the associated side member 15. At their vertical margins, the sides 17 are provided with inwardly projecting, generally oblique extensions 19, the extreme inner edges of which are rolled inwardly to provide tubular guides 20.

The guides 20 of each side slidably receive the lower ends of two legs of a generally U-shaped yoke 25, such yokes being arranged so that their upper ends will co-operate to form a carrying handle, upward movement of the yokes in the guides being limited as by bending the yoke ends as indicated at 25'. In the arrangement illustrated, one yoke is formed so that it may be passed through the other, the legs of the yoke being provided with opposed offset portions 25 which serve resiliently to lock the yokes in crossed relation. Because of the slidable mounting of the yokes in the tubular guides 20, they may be moved between the full-line position and the dotted-line position illustrated in Fig. 1. When in the full-line position, the handle-forming portions of the yokes are above the tops of the

bottles 27 in the carrier, so that those bottles do not interfere with the insertion of the fingers beneath the handle. When, however, the yokes are moved to the dotted-line position shown in Fig. 2, the handle-forming portions of the yokes lie below the tops of the bottles so as not to interfere with the stacking of a series of carriers each full of bottles.

As so far described, the carrier is essentially the same as that shown and described in the co-pending application above referred to. In embodying the present invention in such a carrier, the oblique end portions 19 of the carrier sides are so shaped that when the yokes 25 are interlocked the two tubular guides 20 at each end of the carrier will converge upwardly toward each other. As a result of this convergence, movement of the yoke from the full-line to the dotted-line position shown in Fig. 1 will cause the upper edges of the sides 17 to swing inwardly. As shown, the upper edge of each carrier side is rolled into an inwardly projecting bead 28 which is disposed slightly above the maximum diameter of the bottles 27 with which the carrier is to be filled. Desirably, the device is so proportioned with regard to the size and shape of the bottles it is to convey that when the handle is in the dotted-line position shown in Fig. 1 it will engage the bottles in the two rows and force them together, thus preventing rattling of the bottles and thereby decreasing the possibilities of breakage. Moreover since the beads 28 engage the bottles at points above the maximum diameter thereof, removal of any bottle from the carrier cannot occur when the yokes 25 are depressed. When, however, the yokes are moved upwardly to the position in which they are adapted to serve as a carrying handle, the beads 28 of the upper edges of the sides 17 will be moved outwardly far enough to permit the bottles to be removed.

I claim as my invention:

1. A bottle-carrier, comprising a bottle-supporting bottom and opposite sides swingable relatively to said bottom, a carrying bail for said carrier, said bail having portions associated respectively with said sides, said sides being provided with guides slidably receiving said bail-portions, the guides on opposite sides being disposed to converge upwardly, whereby upward movement of said bail in said guides will cause the upper edges of said sides to move away from each other.
2. A bottle-carrier, comprising a bottle-supporting bottom, sides pivotally connected to said bottom along opposite sides thereof, yokes respec-

engaging with each of the opposite sides of the standing edge of the lock, one of said tool elements being adapted to extend into the lock pocket substantially the full depth thereof for effecting the opening of said pocket, a shaft journaled in said frame, said tools being eccentrically supported on said shaft whereby said tools may be shifted to-

ward and away from said sheet metal member, spring means on said shaft resiliently biasing said tools together, and means for maintaining said tools in a predetermined aligned position as regards the path of movement of said sheet metal member through said machine.

CONRAD H. GREBE.
